CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE

SHEET METAL PAIL

Application filed September 6, 1930. Serial No. 480,104.

This invention relates broadly to sheet metal containers, and more specifically to a pail of the character commonly employed as containers for paints and other fluid and 5 semi-fluid products.

One object of the invention is to provide a sheet metal pail which is suitably stiffened or reinforced about its upper end in such manner that the interior surface of the pail 10 is rendered perfectly plain and smooth throughout.

A further object is to provide a pail having its upper end stiffened or reinforced by means, or in a manner, which permits dispensing with the annularly disposed stiffening beads commonly employed in the bodies of pails at a level below and adjacent to the usual rim roll and which, consequently, 15 obviates the objection to the internal annular channels produced in the formation of such beads.

A still further object is to provide an earless pail having a bail, the attaching means for the bail being wholly exterior to the pail 25 body and not requiring that the pail body be perforated for any purpose, thereby to prevent possibility of leakage at or adjacent to the points of connection of the bail.

In describing the invention in detail, reference is herein had to the accompanying drawing, in which—

Figure 1 is a view, partly in side elevation and partly in section, illustrating a pail embodying my invention; and—

Figure 2 is an enlarged detail section on line 2—2, Fig. 1.

Referring to said drawing, 1 designates the body of a sheet metal pail which is formed with an outwardly turned, or arcuate, 40 rim flange 2 about its top. While said rim flange may be made of any other suitable form, it is herein shown as approximately semi-cylindrical and presenting a downwardly facing channel 3 adapted for the reception of a therewith interlocking portion of the flange of a cover (not shown) seated upon said rim.

Disposed in closely embracing relation to the pail body 1 below the rim flange 2 is a 50 collar-like band 4 of substantial width, as

shown. Said band is preferably formed integrally with the pail body 1 and is folded back upon the metal of said body prior to shaping of the latter—that is to say, while said body metal remains in sheet form. 55 Thus, said band includes a portion 4^a which occupies closely seated underlying relation to and not only complements, but also reinforces, said rim flange 2 in the formation of the rim. Said band is preferably provided with a hem 5 at its lower edge, the terminal portion of said edge being turned back upon itself and being disposed between the band and the pail body, as shown.

Formed in the reinforcing band 4 at each 60 of diametrically opposite points and at a suitable distance below the rim of the pail is an outwardly pressed button 6 of concavo-convex form, the same having a central aperture through which is inwardly projected 65 the hook-like terminal 7 formed on the end of a wire bail 8 of a common or any preferred form.

It is to be noted that the band 4 not only 70 effectively reinforces both the rim of the pail and the body of the pail adjacent to said rim, but also obviates the necessity for providing in said body the annular bead commonly employed for body-stiffening purposes. Moreover, formed in said band rather than in ears 75 attached to the body, the buttons 6 for the reception of the bail terminals possess the advantages over said ears that no rivets or other body-penetrating parts are required; that, therefore, leakage cannot occur at the 80 points of attachment of the bail, and that there are no parts, such as ears, which can be torn off or otherwise detached, releasing the bail.

What is claimed is—

1. A pail of the character described, comprising a body, and a sheet metal band integral with and folded back upon the upper end portion of said body, said band having therein integral outwardly extending buttons 95 adapted for the reception of the terminals of a bail, said band occupying seated relation to said body except at the locations of said buttons.

2. A pail of the character described, com- 100

prising a body having an annular rim portion, and an integral sheet metal band embracing said body at and below said rim portion, said band having formed thereon concavo-convex buttons adapted to have engaged therewith the terminals of a bail and being out of seating relation to said body and said rim only at the locations of said buttons.

3. A container of the character described, 10 comprising a body having an annular outwardly directed rim portion, and a sheet metal band embracing said body and complementing said rim portion in the formation of said rim, said band extending a substantial 15 distance below said rim and having formed therein button-like projections adapted for having engaged therewith the ends of a bail, said projections extending outwardly a distance less than the width of said rim.

20 4. A sheet metal container comprising a body having an annular outwardly flared rim, and a sheet metal reinforcing band embracing the upper portion of said body and extending into said rim, said band having 25 bail attaching means formed thereon and of less depth than the width of said rim.

5. A sheet metal pail comprising a body having an annular outwardly flared rim, and a sheet metal reinforcing band integral with 30 said body disposed in embracing relation to the upper end portion of said body and extending into said rim, said band having therein outwardly pressed apertured buttons for the reception of the terminal hooks of a bail.

35 6. A sheet metal pail comprising a body having the metal thereof folded back into closely seated embracing relation to the upper end portion thereof and constituting a reinforcing band, said band being adapted to have 40 the ends of a bail attached thereto.

7. A sheet metal pail comprising a body having the metal thereof folded back into closely seated embracing relation to the upper end portion thereof and constituting a reinforcing band, said band having formed therein outwardly projecting portions adapted to have the ends of a bail attached thereto.

8. A sheet metal pail comprising a body having the metal thereof folded back into 50 closely seated embracing relation to the upper end portion thereof and constituting a reinforcing band, said band having formed therein outwardly projecting concavo-convex buttons adapted to have the ends of a bail attached thereto.

55 9. A sheet metal container comprising a body having the metal thereof folded back into closely seated embracing relation to the upper end portion thereof and constituting a 60 reinforcing band having bail receiving openings therein, the two engaged thicknesses of metal at and adjacent to the line of the fold being together bent outwardly to form a two-ply rim, said rim protecting said openings from distortion.

10. A sheet metal container comprising a body having the metal thereof folded back into closely seated embracing relation to the upper end portion thereof and constituting a reinforcing band having bail receiving openings therein, the two engaged thicknesses of metal at and adjacent to the line of the fold being together bent outwardly to form an arcuately curved two-ply rim adapted to be interengaged with a cover for the pail body, 70 said rim protecting said openings from distortion.

In testimony whereof, I affix my signature.

CERTIFICATE OF CORRECTION.

Patent No. 1,912,542.

June 6, 1933.

CHARLES H. ROLLASON.

It is hereby certified that error appears in the printed specification of the above numbered patent requiring correction as follows: Page 2, lines 10 and 21, claim 3 and 4 respectively, strike out the word "annular"; and that the said Letters Patent should be read with these corrections therein that the same may conform to the record of the case in the Patent Office.

Signed and sealed this 22nd day of August, A. D. 1933.

M. J. Moore.

(Seal)

Acting Commissioner of Patents.
